Inventor

JOHN NEIMEYER

Chenlon B. Brock
Attorney

UNITED STATES PATENT OFFICE.

JOHN NEIMEYER, OF TRENTON, OHIO.

RAILWAY TIE.

Application filed September 12, 1921. Serial No. 500,156.

To all whom it may concern:

Be it known that I, JOHN NEIMEYER, a citizen of the United States, residing at Trenton, in the county of Butler and State 5 of Ohio, have invented certain new and useful Improvements in Railway Ties, of which the following is a specification.

The invention relates particularly to non-metallic ties, and ties preferably of wood, 10 and is designed especially with the view to providing a tie of this character that may with facility be tamped from the sides and ends in such manner as to provide a maximum bearing surface for the tie, and insure 15 a proper and stable set for the tie in the roadbed. As thus constructed the tie is comparatively inexpensive in cost of production and is capable of being placed and tamped in the roadbed in fixed position to 20 prevent longitudinal or other movement within its bed.

The invention consists in certain novel combinations and arrangements of features in the construction of the tie as will be hereinafter pointed out and claimed. In the accompanying drawings I have illustrated one complete example of the physical embodiment of my invention wherein the tie is illustrated as constructed according to the 25 best mode I have thus far devised for the practical application of the principles of my invention.

Figure 1 is a view in side elevation of a tie constructed according to my invention, 30 showing the rails in section.

Figure 2 is a bottom plan view of the tie of Fig. 1.

Figure 3 is an end view of the tie.

Figure 4 is a longitudinal vertical sectional view at one end of the tie.

In the preferred form of the invention as illustrated in the drawings, the tie 1 is of wood of the usual or standard dimensions and general outline, and the rails 2 that are secured by the spikes 3 are illustrated in Fig. 45 1 to show the relation of parts.

The bottom or underside of the tie, intermediate its ends is rounded or curved transversely as at 4, and at 5, 5, the straight 50 sides of the tie merge with the rounded bottom, these longitudinal edges 5 being also curved, but on a much smaller arc than that of the rounded bottom 4. The rounded bottom and curved edges permit the use of

tamping tools for tamping the material under and around the tie along its sides, and the curved bottom and sides or edges of the tie provide additional bearing surface for the tie in its bed.

At each end the tie is provided with a groove 6 extending from the extremity of the tie toward its center, and at a point 7 approximately under the line of the rail or track, the groove terminates and merges into the rounded bottom 4 of the tie. It will be 65 seen that the ends of the tie are beveled or inclined, the lower ends of these inclined surfaces merging with the bottom of the tie, and the presence of the groove 6 in these beveled ends of the tie form ribs, at 6', at 70 the respective sides of the groove. The groove and the lateral ribs 6' merge with the rounded bottom of the tie just below the point of support for the railway rail 2.

It will be apparent that the tie may be 75 tamped with suitable tools from its ends and the material forced in and under the grooved ends and under the ribs 6', and as thus tamped the tie rests in its bed and is interlocked with the material of the roadbed disposed in the grooves, under the beveled ends of the tie, and about the side ribs 6', 6'. This construction of the tie permits the tamping of the tie into position in its roadbed in such manner as to prevent both 80 lateral and longitudinal movement of the tie, as it will be apparent that the material will hold the tie and prevent either of these movements. The roadbed with ties of this character placed therein is thus rendered 85 more durable, stable, and less likely to require frequent repair.

Having thus fully described my invention, what I claim as new and desire to secure by Letters Patent is—

1. A wooden railway tie having beveled undersurfaces at its ends, and grooves in said faces merging with the bottom of the tie, said grooves forming lateral ribs merging with the bottom of the tie. 95

2. A wooden railway tie having a rounded bottom and beveled undersurfaces at its ends, said undersurfaces having grooves merging with the rounded bottom of the tie toward its center, said grooves forming lateral ribs 100 also merging with the rounded bottom of the tie. 105

JOHN NEIMEYER.
